UNITED STATES PATENT OFFICE.

WATSON R. SMITH, OF JACKSON, MICHIGAN.

SPRING STRUCTURE.

1,126,896.

Specification of Letters Patent.

Patented Feb. 2, 1915.

Application filed February 1, 1912. Serial No. 674,632.

To all whom it may concern:

Be it known that I, WATSON R. SMITH, citizen of the United States, residing at Jackson, in the county of Jackson and State 5 of Michigan, have invented certain new and useful Improvements in Spring Structures, of which the following is a specification.

This invention relates to spring structures for sleeping car berths and has particular 10 reference to upper berths.

One object is to provide a spring structure having the upper convolutions of its springs connected by stays with which and the springs suitable links interlace to provide 15 for an effective connection between the springs and to insure them being maintained in vertical position and in proper spaced relation to one another.

Another object resides in the provision of 20 a spring structure embodying upper and lower frames, one of the frames extending beyond the other at one side and having springs arranged between the frames, with the springs at the sides of the structure prefer- 25 erably of heavier gage wire than the inner springs and with the springs at their top interlaced together by means of stays and links whereby there is provided a substantial, durable and efficient structure which 30 will permit of easy riding.

A still further object is to provide a spring structure embodying a frame with springs in the frame and connected together to maintain them in vertical position and in proper 35 relation to one another, together with means disposed on top of the springs to properly support upholstering material on the springs.

With the above and other objects in view, 40 the invention consists in the construction and novel combination of parts hereinafter more fully described, illustrated in the accompanying drawings and pointed out in the claim hereto appended; it being understood 45 that various changes in the form, proportion, size and minor details of construction may be resorted to without departing from the spirit or sacrificing any of the advantages of the invention.

50 In the drawings:—Figure 1 is a top plan view, parts being broken away. Fig. 2 is an end view. Fig. 3 is a transverse sectional view; and Fig. 4 is a horizontal sectional view through an upper portion of two 55 springs illustrating the underside of the caps which fit on top of the springs.

Referring now more particularly to the accompanying drawings, the reference character 10 indicates a base frame preferably formed of angle iron and 11 an upper frame 60 or border wire which at one side preferably extends beyond the adjacent side of the base frame so as to widen the spring structure as much as possible and to permit it to go as far as possible against the side of the sleep- 65 ing car (not shown).

Secured in any suitable manner to the base frame are transversely disposed spring supports 12 which are preferably arched downwardly, as shown, and which are connected in any suitable manner to longitudinally extending strengthening bands 13 whose ends are directed upwardly, as shown at 14 and secured by rivets or in any other suitable manner to the ends of the base 75 frame.

The transverse spring supports 12 are provided with fingers 15 which are preferably struck out of the metal of the supports and by means of which the lower convolutions 80 of the inner springs are secured. The end spring supports 12 may or may not be provided with these spring connecting fingers, but as shown, the outer springs at the ends of the structure may be secured by means 85 of rivets 16, in which manner the outer springs at the sides are secured to the ends of the spring supports and to the side bars of the base frame, as indicated at 17.

Occupants of berths, particularly upper 90 berths, frequently sit on one side of the berth to remove or put on clothes. It is therefore preferred to have the outer springs at the sides of much heavier gage wire 95 than the innermost springs, although the innermost springs may be of various gages.

Connecting the upper convolutions of the springs will be seen a plurality of stays *a*, each composed of connected links 18 with each link having a coil or eye at each end 100 and each provided with an outward laterally directed V-shaped projecting portion 19. The bodies of these stays engage the tops of the upper convolutions of the springs with the V-shaped projecting portions di- 105 rected outwardly beneath the upper convolutions. The V-shaped projecting portions of links of opposite stays project toward each other and are connected by short stays 20, the ends of the short stays 20 passing beneath the V-shaped portions and upwardly 110 around and over the upper convolutions of

the springs. Thus the stays are connected in series and spaced relation longitudinally of the structure with opposite series of stays connected by the short links 20 to render 5 the long stays *a* rigid and also to aid the long stays in maintaining the springs rigidly in upright position. These short links 20 pass between the upper convolutions and the V-shaped portions of the links of the 10 stays *a* and thereby interlace therewith and are wedged therebetween.

The border springs at the side where the upper frame or border wire 11 projects beyond the base frame have connected to them 15 U-shaped stays 21 by means of suitable clips 22 while the upper convolutions of these particular border springs at their outer sides are connected by a suitable short link 23 whose outer end embraces both the U-shaped 20 stays and the border wire.

To maintain upholstering material at the top of the structure and to prevent it from falling in between the springs, I preferably dispose on top of all of the springs a suitable cap 24, each having a marginal flange 25 and each also having tongues 26 "struck up" therefrom and adapted to embrace the upper convolutions of the springs to secure 25 the caps firmly on the springs, with the por-

tions of said stays engaging the springs disposed between the caps and their fingers. The caps also prevent tearing of bedclothes or upholstering by any roughness due to the springs and their connections. 30

What is claimed is:—

In a spring structure, a frame, helical springs mounted on said frame and extending thereabove, caps resting upon the upper convolutions of said springs, and having marginal flanges embracing said convolutions, links having portions thereof disposed within the cap for interlocking engagement with the upper convolutions of the springs and for engagement with the marginal flanges of the caps and fingers 40 struck downwardly from the caps and engaging the upper convolutions of the springs, and resting upon the links for holding them in engagement with the flanges of the caps, whereby said links will be held 45 rigid relative to the caps and springs. 50

In testimony whereof I affix my signature in presence of two witnesses.

WATSON R. SMITH.
